UNITED STATES PATENT OFFICE.

WILLIAM H. CULKINS, OF ALBION, MICHIGAN.

RAILWAY-CROSSING.

1,144,893.

Specification of Letters Patent. Patented June 29, 1915.

Application filed November 11, 1914. Serial No. 871,539.

To all whom it may concern:

Be it known that I, WILLIAM H. CULKINS, a citizen of the United States, residing at Albion, in the county of Calhoun and State 5 of Michigan, have invented new and useful Improvements in Railway Crossings, of which the following is a specification.

The present invention relates to improvements in railroad crossings.

10 In carrying out my invention it is my purpose to provide a smooth and durable wearing surface for streets, roads and sidewalks at places where they intersect railroads for steam and electric cars. I also 15 aim to provide such a crossing in a plurality of sections each comprising a box-like structure having its bottom slotted or otherwise formed with openings for the passage of moisture, and each of said boxes being filled 20 with suitable bricks so that the wearing surface may at all times be retained in position.

It is a further object of the invention to provide such boxes with flanges which shall contact with the outer sides of the heads of 25 the rails to reinforce and strengthen the said rails and at the same time to reduce the space between the boxes and rails so that only the space between the inner faces of the rails and the outer sides of the inner box 30 member will be presented at the crossing.

With the above and other objects in view, the improvement resides in the construction, combination and arrangement of parts set forth in the following specification and falling 35 within the scope of the appended claims.

In the drawings: Figure 1 is a top plan view of a railway crossing embodying my invention, Fig. 2 is a similar view with the filling blocks removed, Fig. 3 is a transverse 40 sectional view approximately on the line 3—3 of Fig. 1, Fig. 4 is a detail perspective view of one of the outer boxes, Fig. 5 is a similar view of the inner box, and Fig. 6 is a perspective view of one of the filling blocks.

45 Like characters of reference indicate like parts throughout the several views of the drawings.

In the drawings the numerals 1 indicate railway rails and 2 the cross ties of the usual 50 size, shape and material and upon which the rails are secured.

The crossing is broadly indicated by the numeral 3 and includes a central box or receptacle and end boxes or receptacles, all

being of a height to arrange the same flush 55 with the treads of the rails.

The boxes or receptacles are adapted to be secured upon the ties 2 through the medium of spikes or other suitable securing devices, and all of the boxes are of a similar length 60 but the side boxes 4 are preferably of a less width than the central box 5. The boxes are provided with perforated or preferably slatted bottoms 6 so that moisture will find an exit therefrom between the ties 2. 65

The side boxes 4 upon their inner and upper edges are provided with outwardly projecting longitudinally extending flanges 7, and these flanges will contact with the outer faces of the heads of the rails so as to 70 effect in reinforcing the said rails as well as closing the gap which would otherwise be provided between the side boxes and the rails. The central box 5 has its longitudinal edges spaced a distance from the heads 75 of the rails sufficient to permit of the free passage of the flange of the wheels of the rolling stock and both the side and end boxes are filled with blocks 8, preferably in the nature of rectangular plastic bricks 80 which are readily removable and are, of course, interchangeable. The end members of the central boxes 5 preferably have secured to the upper edges inclined platforms 10—10, the said platforms serving 85 as means for directing any article hanging from the train over the crossing.

From the above description, taken in connection with the accompanying drawings, the simplicity of the device, as well as the 90 advantages thereof will, it is thought, be perfectly apparent to those skilled in the art to which such invention appertains without further detailed description.

Having thus described the invention, what 95 I claim is:

1. In a crossing for railways, boxes arranged between and against the outer sides of the rails, the side boxes having their inner and upper edges provided with laterally extending flanges which contact with the outer faces of the heads of the rails, the said boxes being disposed flush with the treads of the rails, and the inner box being spaced from the inner faces of the rails, 100 said boxes having slotted bottoms, means 105 for securing the boxes upon the ties for the rails, and filler blocks comprising removable

and interchangeable members within the boxes and arranged flush with the upper open faces of the boxes.

2. In a railway crossing, a box arranged between the rails, a box arranged to the outer sides of each of the rails, said boxes being flush with the treads of the rails and having foraminous bottoms, filler members comprising bricks arranged within the boxes

and disposed flush with the top of the boxes, 10 and inclined planes arranged upon the opposite ends of the central box.

In testimony whereof I affix my signature in presence of two witnesses.

WILLIAM H. CULKINS.
